UNITED STATES PATENT OFFICE.

TOBIAS NEW, OF BROOKLYN, NEW YORK.

INSULATING CONSTRUCTION.

SPECIFICATION forming part of Letters Patent No. 683,060, dated September 24, 1901.

Application filed February 11, 1901. Serial No. 46,812. (No model.)

To all whom it may concern:

Be it known that I, TOBIAS NEW, a citizen of the United States, and a resident of the borough of Brooklyn, in the city of New York and State of New York, have invented new and useful Improvements in Insulating Constructions, of which the following is a specification, reference being had to the accompanying drawings, forming part thereof.

10 This invention relates to insulating constructions, and has for its objects increased effectiveness in preventing the interchange of heat or cold through the insulating construction, lightness of weight, and cheapness 15 and simplicity of construction, ready transportation of parts prior to erection, strength and durability, non-inflammability, and substantial invulnerability to the effects of fire and water, as well as the capacity of resisting all vapors, gases, and fluids to which such 20 constructions are subjected, and other objects, which will hereinafter more fully appear.

25 My improved insulating construction comprises a block having an outer closed covering and having a plurality of partitions therein, these partitions being spaced or separated by air-spaces, so as to divide the interior of the block into a number of air-spaces between 30 the partitions, and each of these partitions being of cellular construction with a plurality of air-spaces therein.

35 My invention further consists in making such outer envelop of wood and the inner partitions of paper and producing the cellular form of the inner partitions by building up such partitions of flat sheets of paper braced or stiffened and spaced by corrugated sheets of paper.

40 My invention further consists in making the outer envelop air-tight and fireproof and waterproof by coating the same and filling and closing up the pores thereof and filling the joints thereof with a fireproof and water- 45 proof composition and also in making the inner partitions fireproof and waterproof and with tight joints by coating the same and filling up the joints thereof with a fireproof and waterproof composition.

50 My invention further consists in a wall or other structure or construction built up or made up of such insulating-blocks suitably

cemented together; and my invention further consists in cementing such blocks together with a fireproof and waterproof composition 55 or cement and suitable fibrous material to increase the body and adhesiveness thereof.

My invention further consists in certain details of construction, as will hereinafter more fully appear. 60

I will now describe the insulating construction illustrated in the accompanying drawings and will then point out the novel features in claims.

Figure 1 is a front elevation of a wall built 65 up of insulating-blocks and embodying my invention. Fig. 2 is an end elevation of the same. Fig. 3 is a longitudinal transverse section of one of the insulating-blocks.

The insulating-block *a* (shown in section) 70 is a wooden box made up of boards of wood secured together by nails or screws or otherwise and forming a tight and substantial box. Within this box are secured cellular partitions *b*, these partitions being composed of flat sheets of paper with intervening corrugated sheets of paper, the corrugated sheets spacing and stiffening the flat sheets and providing a large number of air cells or spaces within the partitions. Coarse straw-board may be used for these partitions. 75 These cellular partitions *b* are separated from each other with intervening air-spaces, and, as shown, they are held apart by spacing-bars *c*, which may be of wood and which are shown as provided at the tops and bottoms of the partitions and also between the tops and bottoms thereof. The spacing-bars 80 may be held in place by nails or otherwise, and, as will be seen, they space the partitions 85 at these points in their length and further medially divide and separate the air-spaces between adjacent partitions.

The partitions *b*, the spacing-bars *c*, and the outer covering *a* are coated with a fire- 95 proof and waterproof composition, and for such purpose I have employed soluble glass or silicate of soda treated with calcium chlorid. Other substances may, however, be used for such purpose. This coating is applied 100 not only to the surfaces, but also to the joints, and acts as a cement and filling, making the cells or divisions and the structure as a whole air-tight, and thereby insuring that the nu-

merous cells and spaces shall be dead-air spaces or spaces closed from the outer air, containing air in repose, as is highly desirable for effective insulation.

5 The waterproof quality of these blocks is especially valuable for the reason that the blocks are apt to be frequently in contact with water or moist air. The coating of silicate or lime or other practically insoluble, 10 inodorous, and inert substance also insures protection against vapors, gases, and fluids, and the insulation is thus non-absorbent, which is a most important factor in cold storage. The fireproof quality is especially valuable for the reason that the fire risk on refrigerating and cold-storage plants is considered as very high, and therefore the introduction of a non-inflammable and fireproof material in the construction tends to greatly 20 reduce this risk.

I prefer to construct these insulating-blocks by building up the partitions *b* and spacing-bars *c* upon one of the sides of the block as a base with the ends of the block secured in 25 place thereon, and when the partitions and spacing-bars have been thus built up I secure the other side of the block in place. I then dip the structure in the fireproof solution, which may be silicate of soda, holding 30 it, with the open ends, at the top and bottom, so that this solution flows into contact with all of the surfaces and joints thereof, and thereafter I dip the structure in the same manner in the fireproof solution, which may 35 be of calcium chlorid, and thereafter I finish the construction and inclosing of the box, first dipping in the fireproof and in the waterproof solutions the parts not already coated. After the block has been constructed 40 and closed I again dip it in the fireproof and in the waterproof solutions, so as to completely cover the surfaces and seal the joints thereof. It is of course evident that the parts of the blocks may be otherwise assembled and secured together and that modifications may be made in the construction above 45 described within the spirit and scope of my invention.

The insulating-blocks may be used as bricks 50 or slabs in the construction of insulating walls, floors, ceilings, or other structures or constructions, a wall made up of such blocks being illustrated in Fig. 1. In building such a wall or other construction I employ a cement 55 of the fireproof and waterproof composition and place between the blocks a sheet or layer of fibrous material *d*, such as coarse cloth, to add to the body and adhesiveness of the cement and coat the surfaces with the fire- 60 proof and waterproof composition. Such a wall will therefore have air-tight joints and containing, as it does, a very large number of disconnected and dead-air spaces will afford a highly-effective insulation. The individual 65 blocks may be readily transported to the place of construction and will be light and readily handled, and the wall as a whole will be ex-

ceedingly light and inexpensive. Further, where transportation is over great distances the separate partitions and the separate 70 boards for the boxes may be packed closely and the insulating-blocks built up at the place of erection, and thereafter the wall or other construction erected from the insulating-blocks.

What I claim as my invention, and desire to secure by Letters Patent, is—

1. An insulating construction comprising a block having an outer closed covering and having a plurality of spaced partitions therein with air-spaces between them, each of said partitions being of cellular construction with a plurality of air-spaces therein, substantially as set forth. 75

2. An insulating construction comprising 80 a closed wooden box having a plurality of spaced partitions therein, with air-spaces between them, said partitions consisting of thin flat sheets of paper spaced by corrugated sheets of paper, substantially as set forth. 90

3. An insulating construction built of separate blocks, each of said blocks consisting of a closed box having a plurality of spaced partitions therein with air-spaces between them, each of said partitions being of cellular 95 construction with a plurality of air-spaces therein, substantially as set forth.

4. An insulating construction built up of separate blocks, each of said blocks comprising a closed wooden box having a plurality of 100 spaced partitions therein, with air-spaces between them, and said partitions consisting of thin flat sheets of paper spaced by corrugated sheets of paper, substantially as set forth.

5. An insulating construction comprising 105 a block having an outer closed covering and having a plurality of spaced partitions therein, with air-spaces between them, each of said partitions being of cellular construction with a plurality of air-spaces therein, and the covering and partitions being of wood fiber 110 coated with a fireproof and waterproof composition, substantially as set forth.

6. An insulating construction comprising 115 a closed wooden box having a plurality of spaced partitions, with air-spaces between them, said partitions consisting of thin, flat sheets of paper spaced by corrugated sheets of paper, and the box and partitions being coated with a fireproof and waterproof composition, 120 substantially as set forth.

7. An insulating construction built up of separate blocks cemented together with a fire- 125 proof and waterproof composition and a layer of fibrous material between the blocks, each of said blocks being interiorly divided into a plurality of dead-air spaces, substantially as set forth.

8. An insulating construction built up of separate blocks cemented together with a fire- 130 proof and waterproof composition, each of said blocks being of wood fiber coated with a fireproof and waterproof composition, sub- 135 stantially as set forth.

9. An insulating construction built up of separate blocks cemented together with a fire-proof and waterproof composition and a layer of fibrous material between the blocks, each 5 of said blocks comprising a wooden box with interior spaced paper partitions of cellular form, and the partitions and box and joints thereof coated and filled with a fireproof and waterproof composition, substantially as set forth.

10. An insulating construction comprising a closed wooden box having a plurality of in-

terior spaced paper partitions, each of said partitions consisting of two thin flat sheets spaced by a corrugated sheet, and said partitions being coated with a fireproof and waterproof composition, substantially as set forth. 15

Signed at New York, N. Y., this 8th day of February, 1901.

TOBIAS NEW.
